PHASING ARRANGEMENT FOR TELE-FACSIMILE MACHINES

Austin G. Cooley, New York, N. Y., assignor, by
mesne assignments, to Times Telephoto Equipment Inc., New York, N. Y., a corporation of
New York

Application November 28, 1939, Serial No. 306,465

9 Claims. (Cl. 178—69.5)

This invention relates to phasing arrangements and more especially to arrangements for phasing remotely controlled devices, such for example as tele-facsimile machines, telegraph machines and the like.

A principal object is to provide an improved phasing control circuit for tele-facsimile machines.

Another object is to provide an improved automatic phasing control arrangement for a facsimile receiving machine whereby the time required to effect proper phasing is materially reduced.

A feature of the invention relates to a novel form of phasing control or trip magnet for a rotatable device such as a scanning drum, which is conjointly controlled by the drum and by a received phasing signal.

Another feature relates to an improved amplifier and control arrangement for a received phasing signal.

A further feature relates to a novel form of electromagnetic relay.

A still further feature relates to the novel organization, arrangement and relative location and interconnection of parts whereby a simplified and improved phasing control is provided for remotely controlled machines.

Other features and advantages not specifically enumerated will be apparent after a consideration of the following detailed descriptions and the appended claims.

While the invention will be disclosed as embodied in a tele-facsimile system, it will be understood that in certain of its aspects, the invention is applicable to other types of signalling systems or remotely controlled apparatus which are required to be maintained not only in time synchronism but also in spatial synchronism or orientation with a transmitter or the like. Furthermore, the drawing is intended to be schematic and only those parts of a tele-facsimile system are shown as are necessary to an understanding of the features of the invention. Accordingly in the drawings,

Fig. 1 is a schematic diagram of a typical tele-facsimile system embodying the invention.

Figs. 1^A, 1^B and 1^C, are wave diagrams explanatory of the operation of Fig. 1.

Fig. 2 is a detailed end view of the recording drum and trip magnet assembly of Fig. 1.

Fig. 3 is another view similar to that of Fig. 2, but showing the drum and trip magnet in different relation.

Fig. 4 is a detailed top plan view of the trip magnet as shown in Fig. 2.

Fig. 5 is a detailed plan view of the trip magnet as shown in Fig. 3.

Fig. 6 is a lefthand elevational view of the trip magnet.

Referring to Fig. 1, the dotted rectangle in the upper lefthand corner represents any well-known form of tele-facsimile transmitting machine. For a detailed description of such a machine, reference may be had to Patent No. 2,015,742. Merely for explanatory purposes, the machine is shown as comprising a scanning drum 1, driven through suitable gearing 2, by a driving motor 3. The subject matter to be transmitted is wrapped around drum 1 and scanned in the manner well-known in the facsimile art by means of a light source 4 and a light-sensitive cell 5, the drum being rotated and fed longitudinally the width of a scanning line for each complete revolution. For a detailed description of such a drum and associated mechanism, reference may be had to Patent No. 2,138,784. The drum 1 carries at one end, so as to be separate from the subject matter to be transmitted, a blackened band 6 and a small white marker 7, which is adapted to be illuminated by light source 4, once during each revolution of the drum so as to transmit a phasing impulse of relatively large amplitude. The phasing operation is usually effected just prior to the actual tele-facsimile transmission, and for this purpose drum 1 is coupled to motor 3 so that the longitudinal feeding mechanism can be rendered ineffective as described in said Patent No. 2,138,784, whereby the drum can be continuously rotated with the band 6 in optical alignment with source 4 and cell 5 and without longitudinal feeding movement of the drum. Consequently, when drum 1 is rotated at synchronous speed by motor 3, there is generated in cell 5 once per revolution of the drum a special phasing impulse.

Where the tele-facsimile machine is of the type which transmits the signals in the form of a modulated audio frequency carrier e. g. 1800 C. P. S., the output of cell 5 is amplified in a suitable amplifier-modulator 8 whereby the 1800 cycle carrier from source 9 is modulated by the voltages from cell 5. The transmitted phasing signal will therefore consist of a plurality of impulses of 1800 C. P. S. frequency but with the phasing impulses as a whole grouped and spaced at a group frequency determined by the rotational speed of drum 1. Consequently, when the light from source 4 is shining on the black band

6, the 1800 C. P. S. signal will be transmitted over the line L with a uniform and predetermined amplitude as shown by the portions S of Fig. 1^A. Then when the white marker 1 appears before the light source 4, the 1800 C. P. S. carrier has its 6 amplitude very much increased as represented by portions P in Fig. 1^A.

10 The special phasing signals are received at the remotely located receiving station and are amplified in the amplifier 10 of the tele-facsimile receiving machine. The recording lamp of this machine is indicated by the numeral 11 and the last stage of the amplifier which feeds the recording lamp is indicated by numeral 12. A switch 13 is provided for controlling the lamp 15 circuit. The scanning drum 14 of the receiving machine is brought up to synchronous speed by a suitable power motor 15 and thereafter the synchronous speed is maintained by the synchronous motor 16 which is preferably of the phonic-wheel type. The stator or poles 17 of the phonic-wheel motor are arranged to be excited by part of the 1800 C. P. S. signal received from line L after amplification in amplifier 18. Preferably, the toothed rotor of the motor 16 is spring-coupled to the shaft of motor 15 so that the said 20 rotor is capable of limited rotational displacement with respect to said shaft.

25 A push button switch 19 is provided and is normally in the position shown, whereby the circuit from the 60 cycle A. C. supply 20 is disconnected from motor 15. Likewise, when switch 19 is normal as shown, the cathode is connected to ground or the plate return circuit through contacts 23, 24. However, in order to phase the receiving drum 14 with the transmitted drum 1, under control of the phasing signal above described, the attendant at the receiver holds the switch 19 operated for a few seconds. During this time, the motor 15 comes up to speed and rotates drum 14 until it is stopped by a latch 44 and armature 48. A slip clutch 57 permits the motor 15 to continue rotating. When the switch 19 is first operated, it removes the short circuit from around the coupling resistor 25 so that when the phasing signal P of Fig. 1^A is received, it flows through the coupling resistor 25. Resistor 25 is connected to the control-grid 26 and cathode 27 of a pentode amplifier tube 28 through a filter network comprising resistor 29 and condenser 30. This filter is so designed that it suppresses substantially all or the greatest part of the 1800 cycle component of Fig. 1^A, but passes the "group frequency" of the phasing impulses P. Consequently, the output of tube 28 consists of a current having little or negligible 1800 cycle amplitude variations but with the phasing impulses P greatly amplified as represented in Fig. 1^B. The output of tube 28 is then fed to a trigger tube 31 which may be of the grid-controlled gaseous conduction type having its control-grid 32 biased with respect to cathode 33 in any well-known manner so that it does not pass plate current until a phasing impulse of a predetermined minimum amplitude such as that of P Fig. 1^B is impressed on grid 32. Preferably, the output of tube 28 is resistance-coupled by resistor 34 and coupling condenser 35 to tube 31 and through a filter network comprising resistor 36 and condenser 37. This filter, like the filter 29-30 is designed to suppress any 1800 cycle ripple that may be present in the output of tube 28. Consequently, when the phasing impulse shown in Figs. 1^B is impressed on grid 32, the tube 31 passes plate current,

and the resultant applied voltage is substantially a direct current as shown in Fig. 1^C.

10 The plate circuit of tube 31 is traceable from the positive terminal 38 of a suitable D. C. power supply through the winding 39 of the drum trip magnet; the trip magnet contacts 40, 41; plate 42, cathode 33 and resistor 43 to the negative terminal of the D. C. power supply which may be grounded. This circuit, however, is not effective to operate armature 48 of the trip magnet unless the incoming phasing impulse is received at the same time that the contacts 40, 41, are mechanically closed by the drum projection 44 engaging the slide 49 which is carried by the armature. The trip magnet and drum relation are shown in detail in Figs. 2 to 6. As shown in Fig. 2, the trip magnet comprises a magnetic core 45 mounted on an L-shaped iron bracket 46 suitably fastened to the frame 47 of the machine. The armature 48 is pivotally attached as indicated by the numeral 50 between a pair of upstanding lugs on the vertical arm of the L-shaped member 46. The armature 48 has also slidably mounted therein the contact operating member 49, the forward end 51 of which normally projects beyond the forward edge of the armature 48 as shown in Figs. 2, the slide 49 being held in this normal forward position by the contact spring 40a. Spring 40a is attached to the left-hand end of slide 49 by means of an insulator bushing 52. A retaining member 53 is fastened to the top of the armature to prevent the slide from becoming dislodged. The spring 40a is fastened to an insulator block 54 which in turn is fastened to the bracket 46. Also fastened to block 54 is another contact spring 41a carrying the contact 41. When the switch 19 is operated, the armature 48 is held away from the core 45 by means of retractile springs 55 as the winding 39 is de-energized. The end of the armature and the end of slide 51 are in position to be engaged by the stop-latch 44 on the drum immediately after the motor 15 is started (Fig. 2). Before the stop-latch 44 strikes the slide 51, the contacts 40, 41, are open. However, when the drum 14 rotates, the stop 44 engages the slide end 51 and moves the contact 40 into engagement with contact 41 thus preparing the above described circuit for the winding 39. The drum makes a very slight further rotational movement until it engages the end of armature 48 which thereupon acts as a rigid stop and prevents further rotation of the drum. If after the closure of the contacts 40, 41, a phasing impulse is received, sufficient current is passed by the tube 31 to energize the winding 39 thus attracting the armature 48 and removing it from engagement with lug 44. The drum is therefore free to continue its revolution. Once the armature 48 has been operated, and assuming the attendant has in the meanwhile released the push-button 19, the said armature remains attracted to the core 45 by means of a locking circuit traceable from the positive terminal 38, winding 39, resistor 56, contacts 57 and 24, to the negative grounded terminal of the supply source. Thus the armature 48 is maintained out of the path of the stop-lug 44 even after the attendant releases switch 19. From the foregoing, it will be seen that the drum cannot rotate unless the lug 44 engages the slide 49 at the same instant that a phasing impulse is received. If this phasing condition occurs, the drum continues to rotate and the attendant knows that it is in the proper phase relation. It will be

understood of course that a suitable friction coupling 57 is provided between the drum shaft and the motor shaft so as to allow the drum to be stopped for phasing as above described without stopping the motor 15. Motor 15 has sufficient power to keep rotating even though drum 14 is stopped by latch 44. Motor 15 rotates at a speed close to the synchronous speed of motor 16-17, so that as soon as the clutch load is released, the motor 16-17 falls into synchronism in a few thousandths of a second. Thus all that is necessary to effect the phasing operation is to operate the single switch 19 for a short interval of time usually until the drum 14 makes one or two complete revolutions. The operation of switch 19 closes the circuit for the power motor 15 thus bringing the drum 14 up to synchronous speed and the synchronous speed is maintained by the phonic-wheel motor 17. If the drum 14 is in proper phase with the drum 1, then the armature 48 will be attracted by winding 39 at just about the same instant that the lug 44 engages the slide 49 so that a slight click may be heard. If, however, the drum is considerably out of phase, then of course it will be momentarily stopped and the attendant will be thereby apprised of the necessity of holding the switch 19 closed for a further revolution of the drum. When the proper phase relation is obtained, a regular click is heard by the engagement of member 44 and 51, whereupon the attendant may release the switch 19. When the switch 19 is released, the armature 48 is held attracted by the locking circuit above described.

Fig. 2 shows the drum 14 in a position just prior to the engagement of the lug 44 with the slide 49, whereas Fig. 3 shows the drum in its stopped condition wherein the lug 44 causes the contacts 40, 41, to be closed as above described.

While certain specific embodiments and apparatus have been disclosed herein, it will be understood that various changes and modifications may be made without departing from the spirit and scope of the invention.

What I claim is:

1. In a system of the type having rotatable members at different points designed to be run in time and phase synchronism, means associated with one member to transmit a low frequency pulse phasing signal to the other member, a phasing device associated with said other member, and means to render said phasing device automatically effective, the last-mentioned means including a trip magnet, a selective low frequency pulse amplifier whose output controls said magnet, said amplifier being controlled by the said phasing signal, and a switch effective in one position to apply the said phasing signal to said amplifier and effective in another position to maintain said trip magnet operated independently of said amplifier.

2. In a signalling system of the type having rotatable signalling devices at remotely located points designed to be operated in time and phase synchronism, means associated with one device to transmit a carrier wave having its amplitude varied recurrently at low frequency spaced intervals representing a phasing signal, an automatic phasing mechanism associated with the other device including a trip magnet for mechanically stopping said other device when out of phase, a circuit for energizing said trip magnet, said circuit including a filter-amplifier arrangement whereby the amplifier amplifies substantially

only said low frequency signals while substantially suppressing the carrier frequency, means to prepare said circuit including a pair of contacts operated when said other rotatable device is about to be stopped by said trip magnet and means controlled by said amplifier for completing said circuit.

3. A system according to claim 2 in which a manually operable switch is provided to control a locking circuit for said trip magnet independently of said amplifier.

4. A phasing arrangement for the rotary mechanism of a telegraph receiving machine designed to receive a phasing signal from a distant transmitter in the form of a pulsating current having low frequency spaced modulations, said arrangement including an amplifier for the phasing signal, a shiftable stop for engaging said mechanism when out of phase with said transmitter, electromagnetic means for operating said stop, and means to energize said electromagnetic means including a pair of contacts operated when said rotary mechanism is in a predetermined phase, a low frequency pulse amplifier for selectively amplifying said modulations, a rectifier for said amplified modulations the circuit of said electromagnetic means being controlled jointly by said contacts and said rectified modulations.

5. A phasing arrangement for the rotary mechanism of a telegraph receiving machine which is designed to receive a phasing signal in the form of a carrier wave having phasing modulations therein at recurrent low frequency spaced intervals, said arrangement including a shiftable stop for engaging said mechanism when out of phase with said transmitter, electromagnetic means for operating said stop, a circuit for energizing said electromagnetic means including a pair of contacts operated by the engagement between said mechanism and said stop, said circuit also including a filter-amplifier whereby substantially only said low frequency signals are amplified and while substantially suppressing said carrier frequency, and a rectifier for rectifying the output of said amplifier, said rectifier being connected to control said electromagnetic means.

6. A phasing arrangement according to claim 5 in which said rectifier is connected to a grid-controlled gaseous conduction tube having its grid biased so that it is triggered off to pass plate current under control of said rectified output.

7. The combination, a rotatable member to be phased with a distant member under control of received phasing impulses, an electromagnet armature adapted when normal to engage a projection for stopping said rotatable member, a pair of contacts for controlling said armature, and means carried by said armature and engageable by said projection to operate said contacts when the said rotatable member is in a predetermined phase relation.

8. In a signalling mechanism, a rotatable member to be phased with a distant member under control of received phasing signals, an electromagnet armature adapted to be moved into and out of engagement with a projection moving with said rotatable member, a circuit including a pair of contacts controlling said armature, and a member slidably mounted on said armature and arranged to be operated by engagement with said projection to operate said contacts.

9. In combination, means to receive and amplify a carrier wave modulated in accordance with signals, a facsimile scanning drum, power

motive means for bringing said drum up to synchronous speed, synchronous motive means operated under control of said carrier for maintaining said drum at synchronous speed, a phasing trip magnet for said drum, an amplifier for selectively amplifying a received phasing impulse, a switch for controlling the circuit to said power motive means, said switch effective in one pos-

tion to complete said circuit to said power motive means and for applying the said received signals to said amplifier, said switch in another position breaking said circuit to said power motive means and providing a locking circuit for said trip magnet independently of said amplifier.

AUSTIN G. COOLEY.
